UNITED STATES PATENT OFFICE

LOUIS PROPP, OF NEW YORK, N. Y.

DECORATIVE DEVICE

Application filed April 4, 1930. Serial No. 441,503.

This invention relates to decorative devices such as electrically illuminated Christmas wreaths, and the like objects.

An object of this invention is to provide in a device of the character described having a candle simulating electric lighting unit, improved means for quickly and readily mounting said unit on the wreath, said means preferably being adjustable whereby the unit may 10 be attached to wreaths of varying sizes.

A further object of this invention is to provide a neat, compact and rugged device of the character described, which shall comprise few and simple parts; easy to assemble, disassemble and adjust, which shall be comparatively inexpensive to manufacture, and withal practical and efficient to a high degree.

Other objects of this invention will in part be obvious and in part hereinafter pointed 20 out.

The invention accordingly consists in the features of construction, combination of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a front elevational view of a decorative device embodying the invention;

Fig. 2 is a fragmentary, rear elevational view of a device shown in Fig. 1;

Fig. 3 is a cross-sectional view taken on line 3—3 of Fig. 1 with parts broken away to show the interior construction;

Fig. 4 is a perspective view of the clamping attachment;

Fig. 5 is a rear elevational view of a modified construction of the clamp; and

Fig. 6 is a cross-sectional view taken on line 6—6 of Fig. 5.

Referring now in detail to the drawings, 10 designates a decorative lighting device embodying the invention comprising a decorative body such as a Christmas wreath 11 or the like, on which is mounted in the manner hereinafter appearing, an electric lighting unit 14. The wreath is preferably annular 45 in form and for the purpose of illustration

only, is here shown as being semi-circular in cross-section. The wreath comprises an annular core 15 of semi-circular cross-section around which is wound paper rope or the like colored decorative material 16 forming a 55 covering or coating therefor.

The lighting unit 14 comprises a candle simulating tubular member 14a, to the upper end of which is fixed a lamp socket 30a, for receiving a lamp 31a, such as miniature 30 tapered lamp simulating a candle flame. The conductor wires 32a suitably connected to said socket 30a extend thru said tubular member 14a and out thru the lower end 14b thereof.

For mounting the lighting unit 14 on said wreath 11, there is provided a clamp 12, preferably in the form of a two-part extensible member, hereinafter described in detail.

The clamp 12 is made of two adjustable portions 18 and 19. The upper portion 19 70 comprises a flat plate 20, the upper end of which is formed with integral side extensions 21 bent to form a split ring, extending substantially at right angles to said portion 20, for frictionally and detachably receiving the lower end 14b of the tubular candle simulating member 14. Said plate portion 20 is formed with a longitudinal slot 23 for the purpose hereinafter described. The lower portion 18 of the clamp is provided with a 75 plate portion 24 slidably contacting the front face of said portion 20 and having an inwardly folded extension 26 slidably receiving the side edge portions of said plate portion 20. A screw member 25 screwed to said wall portion 24 extends thru said slot 23 and is provided with a head adapted to contact the rear surface of said wall 20 for fixing the clamp portions 18 and 19 to one another.

It will now be understood that the length 90 of the clamp may be adjusted by unscrewing or loosening the screw 25 and sliding the parts 18 and 19 relatively to one another to any desired position, and then again tightening the screw for clamping the plate portions 20 and 24 together.

Extending from the lower end of said plate portion 24 is a forwardly and upwardly curved hook portion 28, aligned with said split ring 21.

The method of mounting the lighting unit 14 on the wreath 11 by means of said clamp 11 will now be clear. The hook portion 28 is first engaged with the lower edge portion 5 of the wreath 11, as clearly shown in Fig. 3, and the clamp then swung forwardly so that the lower edge of the ring 21 engages the top or inner edge of said wreath for firmly clamping a portion of the wreath between said hook 10 and ring. As shown in Fig. 3, the plate portions 20, 24 of the clamp are disposed at the rear or in contact with the flat portion of the wreath. Obviously, for use with wreaths of varying sizes, the length of the clamp may be 15 adjusted, in the manner described above, to the proper length for firmly pressing the hook and ring against opposite side of the wreath.

In Figs. 5 and 6, there is shown a clamp 20 30 illustrating a modified form of my invention. Said clamp 30 is likewise extensible and preferably made of two parts 31 and 32 having interengaging means, described in greater detail hereinafter, to permit relative adjustment of said parts whereby the length of the clamp may be varied to fit wreaths of varying sizes. The part 31 is formed with a flat plate portion 33 terminating at the upper end thereof in a split ring 34 formed with a pair of downwardly projecting prongs 35 for firmly engaging the top of the wreath. Extending outwardly from the lower end of the flat plate portion 33 are a pair of projecting stop members 36 35 for the purpose hereinafter appearing. The part 32 comprises a flat plate portion 37 from the side edges of which there extends a pair of parallel walls 38 slidably receiving therebetween, plate portion 33. Said wall portions 38 are formed with aligned bearing openings 39 rotatably receiving the outwardly extending pintles 40 of a friction clasp 41. Said clasp 41 is preferably formed with a wall 42 adapted to press the plate portion 33 of part 31 firmly against the plate portion 37 of part 32 to bind said parts together as by a frictional clamping action. Said clasp 41 is further provided with a curved handle 43 extending from said wall 42, for 50 causing pivotal movement of said clasp. It will be noted that in the position shown in Fig. 6, with the parts clamped together, the portion 43 contacts the rear surface of the plate 33 for retaining the wall 42 perpendicular to said plate. Wall 37 of part 32 may be formed with an indentation 45 for increasing the frictional contact between the parts. The lower end of part 32 may be formed 55 with a hook portion 46, aligned with the split ring 34, for engaging the underside of the wreath, whereby the wreath may be clamped between said ring and hook portion. For releasing the clasp 41, the handle 43 is merely lifted as by inserting the thumb nail thereunder. The parts 31 and 32 may then be

60 moved to any desired position and the handle again pushed down into contact with plate 33 for clamping the parts together. It will be noted that projections 36 are adapted to contact the ends of walls 38 for limiting extension of the clamp.

The candle unit 14 may be frictionally and 65 removably attached to the clamp 30 in the same manner as the former is attached to the clamp 12. It will now be understood that clamp 30 is extremely easy to manipulate and may be adjusted without using special tools such as screw drivers and the like. It will be obvious that the clamp may be 70 made in one part and hence non-adjustable. Although the wreath, for the purpose of illustration only, is shown as semi-circular in cross-section, it is understood that the clamp 75 may be made of any suitable shape for quickly and firmly engaging the body of a wreath 80 of any desired cross-sectional shape.

It will be noted that the wreath, the clamp 85 and the candle simulating member are separate elements and may be detached from one another and quickly assembled in the manner described above, thus permitting ease in shipment, assembly and also to provide for replacement of one or more of the parts. The lighting unit 14 is mounted on the clamp by merely inserting the lower end 14b of 90 tubular member 14a into the ring 21 which frictionally receives the same, whereby said member is disposed radially inwardly toward the center of the wreath. The conductor wires 32a pass thru the lower end of the member 14a to the rear of the wreath.

It will thus be seen that there is provided a device in which the several objects of this invention are achieved, and which is well adapted to meet the conditions of practical 105 use.

As various possible embodiments might be 110 made of the above invention, and as various changes might be made in the embodiment set forth, it is to be understood that all matter herein set forth or shown in the accompanying drawings, is to be interpreted as 115 illustrative and not in a limiting sense.

Having thus described my invention, I claim as new and desire to secure by Letters 120 Patent:

1. In combination, an annular body, a candle simulating tubular member, and means for mounting said member on said body, said means comprising a member having a portion frictionally receiving one end of said tubular member and contacting a portion of said body and a hook portion extending partially around an opposite portion of said body, whereby said body is clamped between said first portion of said member and said hook portion of said member.

2. A device of the character described comprising a wreath, an electric illuminating unit, and friction means for removably 125

mounting said unit on said wreath, said means comprising a pair of relatively adjustable portions, and means for fixing said portions to each other in adjusted position.

3. In combination, a wreath body, a member having a hook portion engaging a portion of said body, and a tubular member, said first member being provided with a portion frictionally engaging said tubular member and contacting an opposite portion of said body whereby said body is clamped between said hook portion and said other portion.

4. In combination, a decorative body, a lighting unit including a tubular candle simulating member, and means for mounting said unit on said body, said means comprising a member having portions contacting opposite sides of said body, one of said portions being adapted for frictional attachment to the lower end of said candle simulating member.

5. In combination, a clamp comprising an intermediate portion, a hook extending from one end of said portion, and a ring extending from the opposite end of said portion, said ring and hook being aligned, and a wreath body having a portion extending between and contacted by said hook and ring.

6. In combination, a tubular candle simulating member, a clamp comprising an intermediate portion, a hook extending from one end of said portion, a ring extending from the opposite end of said portion and frictionally engaging said tubular member, said ring and hook being aligned, and means on said clamp for adjusting the distance between said hook and ring.

7. In combination, a wreath, a clamp having a hook portion adapted to engage a portion of said wreath, a split ring portion adapted to contact an opposite side of said portion of said wreath, and a candle simulating member frictionally received in said split ring.

45 8. In combination, a wreath, a clamp having a hook portion adapted to engage a portion of said wreath, a split ring portion adapted to contact an opposite side of said portion of said wreath, a candle simulating member frictionally received in said split ring, and means for adjusting the distance between the hook portion and ring.

9. In combination, a wreath, an extensible clamp attached to said wreath and a candle simulating member mounted on said clamp, said clamp comprising a pair of relatively adjustable parts and pivotal means for clamping said parts together.

10. In combination, a wreath, an extensible clamp attached to said wreath and a candle simulating member mounted on said clamp, said clamp comprising a plurality of relatively adjustable parts, one of said parts having a flat plate portion and a pair of parallel walls extending therefrom, said other parts

having a flat plate portion received between said parallel walls, and means mounted on said parallel walls for pressing said plate portions together.

In testimony whereof I affix my signature.

LOUIS PROPP.
